DIE FOR MARKING PLANS OF
ORNAMENTATION

Joseph L. Valiquette, Lowell, Mass.

Application April 1, 1929, Serial No. 351,775

2 Claims. (Cl. 101—368)

This invention relates to a method and article for marking plans of ornamentation and is particularly adapted for laying plans of ornamentation on preformed shoe-parts.

5 An object of the invention is to provide, in a manner as hereinafter set forth, for marking a plan of any predetermined ornamentation upon a preformed part of a shoe, such as a vamp or quarter, so as to furnish a plan to be followed in 10 stitching or otherwise decorating the shoe in conformity with the plan.

Another object of the invention is to provide a die or mat to be utilized in the marking of the plan which is extremely simple in its method of 15 assembly, wherein the raised marking surface on the mat may be formed to the predetermined ornamentation and applied thereto in a very simple manner, while at the same time providing a strong, durable and compact plate comparatively inexpensive to manufacture and install.

20 Another object of the invention is to provide a press for applying the markings that coats and applies the ornamental plan of marking in one operation and to further provide an indicator to 25 assure centering of the shoe part with respect to the die or mat.

A further object of the invention is to provide a 30 press of the character referred to that is strong, compact and durable, highly efficient for its intended purpose, thoroughly reliable in its operation and comparatively inexpensive to manufacture and assemble.

With the foregoing and other objects in view, the invention consists of a novel method, combination and arrangement of parts as will be 35 hereinafter more specifically described and illustrated in the accompanying drawings, wherein is disclosed an embodiment of the invention, but it is to be understood that changes, variations and 40 modifications may be resorted to without departing from the spirit of the claims hereunto appended.

In the drawings wherein like reference characters denote corresponding parts throughout the 45 several views:

Figure 1 is a detailed longitudinal sectional view of the device in accordance with this invention,

50 Figure 2 is a central detailed transverse sectional view thereof, taken substantially on line 2—2 of Figure 1 and looking in the direction of the arrows,

55 Figure 3 is a top plan view partly in section taken substantially on line 3—3 of Figure 1 and looking in the direction of the arrows,

Figure 4 is a top plan view of the templet in accordance with this invention,

Figure 5 is a top plan view of the die or mat,

Figure 6 is a sectional view taken substantially on line 6—6 of Figure 5,

Figure 7 is a top plan view of a preformed part of a shoe illustrating a plan of ornamentation marked thereon in accordance with this invention, and

Figure 8 is a perspective view, broken away and 10 illustrating the method of assembling the die or mat in accordance with this invention.

Referring to the drawings in detail, wherein is disclosed an embodiment of the invention, 10 indicates a substantially rectangular metallic 15 base having opposite sides 11, 12 rising therefrom at one end of less height than the sides 13, 14 rising from the base at the other end thereof.

The sides 11, 14 merge with each other at one 20 side of the base whereas the sides 12, 13 merge with each other to form the opposite sides of the base. Rectangular filler blocks 15 are supported 25 between the opposite sides of the base and are supported on inwardly directed flanges 16, 17 formed integral with the sides thereof. The filler blocks 15 may be formed of wood or other like material so as to present a softer bearing surface to the parts brought into abutment therewith.

A transverse rib 18 is disposed across the base 10 adjacent the raised sides 13, 14 and the said 30 sides are provided with an inwardly directed flange 19, 20 under which is anchored in abutting relation to the rib 18 a color absorbing pad 21 which applies the color to the die or mat as will be presently described. The color pad 21 is disposed 35 at one end of the plate as will be clearly seen by referring to Figure 3 of the drawings.

A templet 22 is disposed across the other end of the base and is of flat contour. Adjacent the center of the templet 22 openings are formed 40 therein of a configuration of any part of a shoe, such as a quarter, a vamp or the like and said configurations are indicated at 23, 24.

The templet is formed with three openings indicated at 25, 26 and 27, two of which 25, 26 are 45 located along the longitudinal median of the templet, whereas the third opening 27 is located to one side of said median. The circular openings 25, 27, have a pair of thumb screws 28, 29 extending through, having the thumb nuts 30, 31 with 50 the top face of the templet 22.

It will be noted that the openings 25, 27 are disposed in an angular relation to the longitudinal median. A pin 32 is anchored in the filler block of the base and projects through the open- 55

ing 26 in spaced relation to the walls surrounding the openings so as to form a guide for centering the templet.

The leg portions 33, 34 of an inverted U-shaped handle are rockably mounted on the raised sides 13, 14 as indicated at 35, 36 and the bight portion 37 of the handle is formed with an upstanding gripping portion 38. To one side of the gripping portion 38, a spring 39 is secured to the bight portion 37 of the handle as indicated at 40, the other end of the spring, not shown in the drawings, may be attached to the ceiling or other fixed support so as to automatically retain the handle in vertical position with respect to the base.

15 A substantially U-shaped plate bar has the opposite legs 41, 42 rockably connected with the opposite legs 33, 34 of the yoke-shaped handle intermediate the ends of the legs as indicated at 43, 44. One end of a pair of longitudinally spaced 20 rocker arms 45, 46 are rockably mounted to the raised side 14 as at 47, 48, while the upper ends thereof are rockably mounted to the one side 42 of the platen bar as at 49 and 50.

The spaced rocker arms 45, 46 not only provide reinforcements for the platen bar but also insure the rocking movement to describe a path of a fixed radius. A pair of similar rocker arms 51 are similarly mounted on the opposite side of the platen bar alike in every respect to the pair 30 of rocker arms 45, 46.

35 A pair of guide pins 52, 53 are anchored in a die lock or mat 54 and extends through the bight portion of the platen as will be understood by reference to Figure 2 of the drawings. The die 54 is secured to the bight portion of the platen by means of a countersunk thumb screw 55 which projects through an opening in the platen bar and is secured by means of a thumb nut 56.

40 The die or mat may be formed of wood so as 40 to provide proper anchorage for the configuration which is to be secured to the lower face thereof.

45 Formed on the lower surface of the die block 54 is a pair of dies indicated generally at 57, 58 which may be attached thereto by suitable hold fast devices. The dies 57, 58 may be of any predetermined ornamentation for the purpose of transferring the plan to the leather shoe part in a manner to be presently referred to.

50 Each of the dies 57, 58 are formed in the same manner and it is believed that a description and a method of forming the same, in connection with either one will suffice for teaching the formation of any die of any ornamentation in accordance 55 with this process. When it is desired to form ornamental raised surfaces, where the surfaces are in close proximity to each other, the die platen 59 is slotted as indicated at 60, 61 having the outer edges of the slot in conformity with the ornamentation desired to be applied.

60 A flat brass, or other copper alloy material 62 is placed edgewise in the slots 60 or 61 in abutting relation to the outer edges thereof and soldered to the plate 59 as indicated at 63. The strap 62 is shown at 64, 65 of two different configurations formed in accordance with this invention.

65 Where a single line of ornamentation is desired, the edge of the platen 59 may be cut to the desired 70 ornamentation, as is clearly shown in Figure 8 of the drawings at 66, the strap 62 may be bent to conform with the edges 66 and soldered in the angle between the abutting strap 62 and the upper face of the plate 59, whereby a very economical method of fabricating the die is carried out.

When the adaptation of the ornamentation takes a form as shown in Figure 5 of the drawings, and particularly along a transverse line illustrated at 6-6 in the drawings, a slot 67 is formed adjacent the cut out portion 61 and the strap 62 is bent to conform with the configuration of the edge of the slot which follows the form of the desired ornamentation, and is then soldered in abutting relation to that wall of the slot as indicated at 68. The latter method is carried out 10 when a cut out portion at 61 occurs in close proximity to another line of configuration as will be clearly understood by referring to Figure 5 of the drawings and particularly along the line 6-6 thereof. I can make slots of any reasonable width 15 and of a depth which preferably does not go through the plate 59 making, however, one certain edge of a slot to conform to the desired ornamentation. In this way, I avoid using two plates and avoid the necessity of cutting an accurate, 20 narrow slot to just fit the width of the strip to be inserted thus saving expense and gaining in accuracy.

25 After the die plate 59 has been provided with the desired ornamental effect as heretofore described, the plates may be secured to the die block 54 by tacks or other suitable hold fast devices. The die block is then attached to the platen bar.

30 The template 22 is maintained in abutting relation to the filler blocks 15 by means of T-shaped resilient clips 69, 70 bulged outwardly so as to exert pressure on the ends when the thumb nuts 30, 31 are screwed downwardly thereon. At the inner section of the stem and the sides of 35 the T-shaped clip 69, 70 is formed with an opening through which the thumb screws 28, 29 extend and the thumb nuts 30, 31 are thereby brought into engagement with the upper bulged faces of the clips.

40 The pressure exerted by the clips 69, 70 contain the templet 22 in a substantially rigid relation with the base of the press.

45 In the application of the device, in accordance with this invention, the templet 22 is provided with cut out portions 23, 24 of a configuration to conform with the part of a shoe to be ornamented. As shown in Figure 3 of the drawings, the cut out portions 23, 24 conform to the form of a shoe part illustrated in Figure 7 of the 50 drawings. The pre-formed shoe part indicated generally at 71 in Figure 7 of the drawings, is placed with the edges thereof in abutment with the edges of the cut out portion 23, 24 and the handle 38 is moved to the end of its stroke, whereupon the edges of the brass strap 62 on the dies 57, 58 are brought into abutment with the absorbent coloring pad 21 and are thereby coated.

55 The handle is then moved in the opposite direction to the end of its stroke whereupon the coated edges of the strap 62 are brought into abutment with the leather shoe part 71 in the cut out portions 23, 24 whereupon the ornamentation will be marked on the leather shoe part as indicated generally at 72 in Figure 7 of the drawings.

60 In applying the templet member 22 to the filler block 15 of the press, the thumb screw 30, 31 are removed and the openings 25, 27 inserted thereover. The spring clips 69, 70 are then brought into engagement with the top of the templet and the thumb screws 30, 31 screwed down tightly so as to exert pressure in various places on the templet to prevent shifting thereof during the transferring of the ornamentation.

65 The guide pin 32 will be inserted in the open- 75

ing 26 and by gauging the distance from the guide pin to the wall surrounding the opening 26 the templet 22 may be centered properly.

Having thus described my invention, what I claim as new is:

1. In a mat for transferring plans of ornamentation, a base having certain of its edges conforming to plans of ornamentation, and furthermore provided with apertures having certain edges thereof conforming to plans of ornamentation, and strips of material coupled to the base along said certain edges of the base and apertures.

2. In a mat for transferring plans of ornamentation, a base having certain of its edges conforming to plans of ornamentation, and furthermore provided with apertures having certain edges thereof conforming to plans of ornamentation, strips of material coupled to the base along said certain edges of the base and apertures, and said strip projecting above the plane of the base and in abutment with said certain edges of the base, and apertures. 10

JOSEPH L. VALIQUETTE.
